[57] CLAIM

The ornamental design for a gift package, as shown and described.

DESCRIPTION

FIG. 1 is a top plan view of a gift package showing my new design;

FIG. 2 is a left side elevation thereof, the right side elevation being a mirror image;

FIG. 3 is a front elevation thereof, the rear side elevation being a mirror image;

FIG. 4 is a bottom plan view thereof;

FIG. 5 is a sectional view taken along line 5—5 of FIG. 1;

FIG. 6 is a top plan view of the first modified form of FIG. 1;

FIG. 7 is a left side elevation of FIG. 6, the right side elevation being a mirror image;

FIG. 8 is a front elevation of FIG. 6, the rear side elevation being a mirror image;

FIG. 9 is a bottom plan view of FIG. 6;

FIG. 10 is a sectional view taken along line 10—10 of FIG. 6;

FIG. 11 is a top plan view of a second modified form of FIG. 1;

FIG. 12 is a left side elevation of FIG. 11, the right side elevation being a mirror image;

FIG. 13 is a front elevation of FIG. 11, the rear side elevation being a mirror image;

FIG. 14 is a bottom plan view of FIG. 11;

FIG. 15 is a sectional view taken along line 15—15 of FIG. 11;

FIG. 16 is a top plan view of a third modified form of FIG. 1;

FIG. 17 is a left side elevation of FIG. 16, the right side elevation being a mirror image;

FIG. 18 is a front elevation of FIG. 16, the rear side elevation being a mirror image;

FIG. 19 is a bottom plan view of FIG. 16; and

FIG. 20 is a sectional view taken along line 20—20 of FIG. 16.
